(57) **CLAIM**

The ornamental design for an umbrella handle with a snow globe mounted on its end, as shown and described.

DESCRIPTION

FIG. 1 is a perspective view of an umbrella handle with a snow globe mounted on its end embodying my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and

FIG. 7 is a rear elevational view thereof; and,

FIG. 8 is a perspective view of a second embodiment of an umbrella handle with a snow globe on its end.

The broken line showing of a figure and base is for illustrative purposes only and forms no part of the claimed design.
